UNITED STATES PATENT OFFICE

2,329,344

BOWLING GAME

Vincent C. Engstrom, Los Angeles, Calif.

Application December 9, 1941, Serial No. 422,210

1 Claim. (Cl. 273—45)

This invention relates generally to games and game devices.

It is a primary object of my invention to provide a simple portable device for playing a simulated tenpin bowling game. In this connection, it is an object to provide a game board providing a flat surface for supporting tenpins or playing pins and to provide means for supporting a swingable pin striking element for knocking the pins down.

It is a particular object of my invention to provide a simple effective means for manually simultaneously setting all of the pins in their proper place on the game board surface after they have been knocked down by the striking element. In this respect it is an object to provide a pull or movable member which can easily be grasped by a player and which is connected by flexible means with the various pins so that operation of the pull will cause the pins to assume an upright and predetermined position on the game board.

Although it is my purpose to provide a device which is particularly designed for use as a small game indoors or the like, I contemplate that in its general aspects the invention is suitable for use on a larger scale and it is therefore an object of my invention to provide suitable apparatus for playing a simulated bowling game with standard or large size tenpins together with means for manually resetting the pins in an easy manner.

These and other objects will be apparent from the drawing and the following description thereof. Referring to the drawing:

Fig. 1 is a perspective view of a game device embodying a preferred form of my invention;

Fig. 2 is a top plan view of the game board and objects thereon, the pin striking element suspension means being shown in section;

Fig. 3 is a fragmentary plan view of the bottom of the board of Fig. 2;

Fig. 4 is a fragmentary enlarged cross section on the plane indicated by line 4—4 of Fig. 2;

Fig. 5 is a fragmentary enlarged cross sectional view of the pull member, the plane being on line 5—5 of Fig. 2; and

Fig. 6 is an enlarged central sectional elevation of the pull member and adjacent portion of the game board, the plane of the section being indicated by line 6—6 of Fig. 3.

More particularly describing the invention, the game device includes a game board 11 which is adapted to be supported in a horizontal plane on any suitable surface such as a table or the like. This member provides a flat surface 12 for supporting a plurality of playing pins or tenpins in-

dictated by numeral 14. The game board itself may be constructed in any suitable manner, however, the one illustrated comprises a boundary frame consisting of the four rails 15 having internal channels or grooves 16 to accommodate and mount the flat plate-like board or panel 17.

It is a feature of my invention that a pin striking element be provided in such a manner that it can be swung past the tenpins by a player in a manner similar to a pendulum with the object of having it knock down the pins on its return swing. In order to accomplish this, a frame, generally indicated by numeral 18, is provided extending above the surface 12. This frame is shown as a tripod and comprises three upwardly extending rods 19 which are removably mounted within holes 20 in the rails 15 of the game board. At their upper ends the rods are removably mounted in a block 22 which supports a flexible line 23. A striking element 24 is mounted at the lower end of the line, the line being of such a length that the striking element when at rest as shown in Figs. 1 and 2 occupies a position slightly above the game board surface 12 and below the tops of the playing pins. The pin striking element preferably also normally hangs in a position slightly to one side of the leading pin. The striking element 24 is spherical and may be formed of any suitable material, rubber being a desirable substance.

In playing the game, the player grasps the striking element 24 and moves it to a position behind the foul line shown in Fig. 2 where he releases it with the object of having it swing past the playing pins without touching them on its first or forward swing and having it hit them and knock down as many as possible on its return swing. Any suitable rules may be provided for playing the game. Under whatever rules followed, after a player has had all of the swings permitted, the pins which may have been knocked down are reset. It is a particular feature of my invention to provide means whereby the resetting of the pins can be quickly and easily accomplished. For this purpose a pull member 26 is provided near one margin of the game board. This pull is located within a slot 27 in the panel 17 and has a top portion 28 extending above the board where it can easily be grasped by the fingers of an operator. A portion 29 is slidably received in the slot 27 while the bottom portion 30 is disposed beneath the board 17.

In order to operate the pins for resetting, each pin is provided with a cord or line 32 which is securely mounted in the lower end of the pin

in any suitable manner. The panel 17 is provided with a plurality of guide holes 33 which are located in predetermined positions where it is desired to have the pins stand. These guide holes receive the lines 32 extending from the individual playing pins. The lines 32 are attached to the bottom portion 30 of the pull 26 and are of such a length with respect to the pull and the individual pins that movement of the pull 26 toward the edge of the game board serves to erect or set the pins in place over their respective guide holes.

I preferably provide an elastic means at some point between the individual pins and the pull member and in the form of the invention shown this means comprises a sheet of rubber 35 which is clamped to the pull by a plate 36 and screw 37, the latter serving to hold the parts of the pull together. The individual lines 32 leading to the pins may be attached to this sheet in any suitable manner, however, one way of doing this is to provide a single line 32 for each pair of playing pins and mount the ends of the line in the respective pins and have the intermediate portion of the line received in a pair of openings 39 and 40 in the rubber sheet. This is most clearly illustrated in Fig. 6.

With the provision of an elastic means at some point between the pull 26 and individual pins the life or wear of the individual lines is greatly increased. At the same time such means acts as a compensating means to take care of any irregularity in the length of the lines. Thus, by using the elastic compensating element it is unnecessary to provide lines 32 which are accurate in length with respect to each other and

the individual pins to which they extend so that they will be simultaneously tautened when the pull is moved away from the pins. It is contemplated of course that some other elastic means 5 might be utilized as for example an individual coil spring might be provided in each line or between each line and the pull member.

With the construction shown and described movement of the pull 26 away from the pins 10 serves to simultaneously set the pins in proper position over the respective guide holes, making a convenient and easily operable device for resetting the pins during the playing of the game.

Although the invention has been particularly 15 shown and described it is contemplated that various changes and modifications can be made without departing from the scope of the invention and it is intended to cover such changes and modifications as come within the claim.

I claim as my invention:

In a game device, a game board having a playing 20 surface provided with a plurality of relatively small guide holes extending therethrough, playing pins adapted to stand on said surface over the respective guide holes, a pull 25 slidably mounted in said game board and positioned at a point remote from said pins, said pull having a portion extending underneath the surface upon which the pins stand, an elastic member mounted on the portion of said pull extending beneath said surface, and a line connecting each pair of pins with said elastic member, each line having its ends attached to the respective pins and an intermediate portion attached 30 to said flexible member.

VINCENT C. ENGSTROM.
